ATTORNEY

UNITED STATES PATENT OFFICE.

ARMIN BORZSONY, OF NEW YORK, N. Y.

LOUD SPEAKER.

Application filed June 9, 1923. Serial No. 644,436.

To all whom it may concern:

Be it known that I, ARMIN BORZSONY, a citizen of the United States, and a resident of the borough of Manhattan, city, county, and State of New York, have invented certain new and useful Improvements in Loud Speakers, set forth in the following specification.

This invention relates to telephonic receivers of the loud speaker type, and more particularly is applied to apparatus of this character, which is particularly adapted for use in the reception of radio telephony.

The object of the invention is to construct a loud speaker of simple efficient construction which will coordinate a permanent magnet with the armature and the sound box in an improved manner.

The above and further objects of the invention will better be understood by reference to the illustrative embodiments described in the following specification and shown in the accompanying drawings solely for purpose of illustrating the claims which are directed to these embodiments solely for the purpose of illustration and not limitation.

In the drawings, Fig. 1 is a vertical section partly diagrammatic of the inverted apparatus.

Fig. 2 is a bottom plan view.

Fig. 3 is a detail section, parts shown in elevation and all drawn to an enlarged scale of the armature and core construction, and Fig. 4 is a view similar to Fig. 3, showing a modification.

Fig. 5 discloses a modification of the fastening means.

A sound box A of any approved construction, providing the sound duct 1, adapted to be connected with any amplifier, such as a horn, is circular in construction and mounts the usual diaphragm 2. The diaphragm 2 is sound-insulated opposite rubber gaskets 3 and 4, the flanged ring 5 being secured to the plate 6 in any approved manner.

A permanent magnet B comprises an open ring-shaped portion 7 embracing and mounting the sound box A. In the embodiment illustrated, screws 8 pass through suitable perforations in the portion 7 and have screw-threaded engagement with the sound box wall 9, although it is contemplated that the same screws might be threaded into the permanent magnet and operate as set screws with their noses jamming against the sound

box 9. Such construction is shown in Figure 5 in which the set screws 8' adjustably hold the permanent magnet and the associated electromagnetic means relatively to the sound box A and armature C by jamming against the sound box wall 9. This adjustment is independent of the adjustment of the cores 12' and 13' shown in Figure 4.

In the construction of the permanent magnet B, offset poles 10 and 11 form continuations of the ends of the open ring portion 7. To these poles are suitably secured a pair of L-shaped cores 12 and 13, adapted to mount the usual coils 14 and 15. If desired, these cores, instead of being L-shaped, may be substantially U-shaped as indicated for the cores 12' and 13' of Fig. 4 and be adjustably secured to the poles 10 and 11 by screws 16 and 17 working in slots 18 and 19. The shoulders 20 and 21 serve to maintain the upright position of the cores 12' and 13'.

In fact, for some purposes, the configuration of the permanent magnet construction illustrated is not essential although convenient in rendering the construction compact; likewise in connection with the armature lever which is shown with an approximate 3 to 1 ratio of movement amplification from the armature to the diaphragm. It is to be understood that this leverage ratio may be modified to accommodate varying conditions. The magnet B may be laminated or in sections.

The armature C is arranged to overlie the core tips of the cores 12 and 13 or 12' and 13' and may be adjustably mounted by the stem 23 and set screw 24 in one end of the fulcrumed amplifying lever 25, the other end 26 of which is attached in an approved manner to the diaphragm 2.

The fulcrum for the lever 25 may be mounted conveniently between the permanent magnet poles 10 and 11 and as shown comprising a pair of brackets 30 and 31, carrying the adjustable trunnion screws 32 and 33.

The inventive thought may have a variety of expressions as is contemplated in what I claim and desire to secure by United States Letters Patent as follows:

1. In a loud speaker, a sound box having a vibratory diaphragm; a fulcrum bracket fixed to said sound box; a multiplying sound vibration lever fulcrumed to said bracket and with the end of its long arm attached to said

diaphragm; an armature operatively secured to the short arm of said lever; a permanent magnet of the horse-shoe type; separate cores operatively secured to said permanent magnet; energizing coils for said cores; means for securing said permanent magnet directly to said sound box with the poles of said cores in cooperative relation to said armature; and means for adjusting the operative spacing between said armature and said poles independently of the means for securing said permanent magnet to said sound box.

2. The structure as described in claim 1 and further characterized by the fact that the bounding planes of said permanent magnet and of said diaphragm are substantially parallel and the cores are L-shaped so as to present pole faces in a plane substantially parallel with that of said diaphragm.

3. In a loud speaker, a permanent magnet in the shape of an open circular ring with outstanding poles; coil mounting cores; a circular sound box having a diaphragm, said sound box being held in the circular ring of said permanent magnet; and a fulcrumed lever-mounted-armature cooperating between said cores and said diaphragm.

4. In a loud-speaker, a vibratory diaphragm; a rigid mounting for said diaphragm; rigid fulcrum bracket means fixed to said mounting for said diaphragm; an amplifying lever of the first order, having the end of its longer arm attached to said diaphragm; an armature on the shorter arm of said lever; means fulcruming said lever to said fulcrum bracket means unwieldingly against any operative force applied to said lever through said armature and electromagnetic means free from contact with said armature for operating said diaphragm by magnetic action on said armature in response to sound controlled current variations.

5. In a loud speaker, a vibratory diaphragm; a rigid mounting for said diaphragm; rigid fulcrum bracket means fixed to said mounting for said diaphragm; an amplifying lever of the first order, having

the end of its longer arm attached to said diaphragm; an armature on the shorter arm of said lever; means fulcruming said lever to said fulcrum bracket means unwieldingly against any operative force applied to said lever through said armature; electromagnetic means comprising a core for cooperation with said armature, a winding and a permanent magnet; and means for adjustably securing said electromagnetic means relatively to said rigid mounting for said diaphragm.

6. In a loud-speaker, a vibratory diaphragm; a rigid mounting for said diaphragm; rigid fulcrum bracket means fixed to said mounting for said diaphragm; an amplifying lever of the first order, having the end of its longer arm attached to said diaphragm; an armature on the shorter arm of said lever; means fulcruming said lever to said fulcrum bracket means unwieldingly against any operative force applied to said lever through said armature; electromagnetic means comprising a core for cooperation with said armature, a winding and a permanent magnet; and means for adjustably securing said electromagnetic means relatively to said armature.

7. In a loud-speaker, a vibratory diaphragm; a rigid mounting for said diaphragm; rigid fulcrum bracket means fixed to said mounting for said diaphragm; an amplifying lever of the first order, having the end of its longer arm attached to said diaphragm; an armature on the shorter arm of said lever; means fulcruming said lever to said fulcrum bracket means unwieldingly against any operative force applied to said lever through said armature; means for adjusting the separation between said armature and the cooperative polar face of said electromagnetic means.

In witness whereof, I have signed my name to this specification, this 18th day of May, 1923.

ARMIN BORZSONY.
